Primary Examiner — Sheryl Lane*Assistant Examiner* — Ieisha N Price(74) *Attorney, Agent, or Firm* — Muncy, Geissler, Olds & Lowe, P.C.(57) **CLAIM**

I claim the ornamental design for a corner bracket, as shown and described.

DESCRIPTION

FIG. 1 is a front, top and right side perspective view of a corner bracket showing my new design;

FIG. 2 is a rear, bottom and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
